No. 818,728.

PATENTED APR. 24, 1906.

H. WONDERLICH.
IRONING MACHINE.
APPLICATION FILED MAY 8, 1905.

UNITED STATES PATENT OFFICE.

HERMAN WONDERLICH, OF PROVIDENCE, RHODE ISLAND.

IRONING-MACHINE.

No. 818,728.

Specification of Letters Patent.

Patented April 24, 1906.

Application filed May 8, 1905. Serial No. 269,288.

To all whom it may concern:

Be it known that I, HERMAN WONDERLICH, a citizen of the United States, residing at the city of Providence, in the county of Providence and State of Rhode Island, have invented certain new and useful Improvements in Ironing-Machines, of which the following is a specification, reference being had therein to the accompanying drawings.

10 This invention relates to ironing-machines, and has for its object to produce a simple and comparatively inexpensive device adapted more particularly for household use to reduce the labor of ironing.

15 In ironing clothes with the ordinary flat-iron it is necessary that the iron should be pressed with considerable force down on the fabric in order to obtain the desired finish on the same. To maintain this pressure with

20 the arms for any length of time is extremely fatiguing, and for this reason ironing by many women is prohibitive. To obviate this difficulty, I have provided an ironing-board which may be attached to any bench 25 or table and that is provided with means for automatically applying the desired pressure to the iron, thereby making it necessary to simply slide the iron back and forth over the face of the goods.

30 By the use of my improved device the labor of ironing is reduced to the minimum and the finest quality of work may be produced.

The invention is fully set forth in this specification and more particularly pointed out 35 in the appended claims.

In the accompanying drawings, Figure 1 is a perspective view of my ironing-machine, showing the same clamped to a table. Fig. 2 represents the device as turned out at right 40 angles from the table, in which position it is often desired to be used when ironing dresses or other large articles. Fig. 3 is a detail view showing the ball-and-socket joint, the vertical adjustment of the tension-rod with its

45 lower end engaging the recess in the iron. Fig. 4 represents the device as collapsed or folded in position for convenience in stowing away. Fig. 5 is a detail view of the supporting-legs, showing the means by which they 50 may be attached to the lower side of the ironing-board. Fig. 6 is a top view of the fixed plate 2, showing the arrangement of the fingers 3 3 and the two ears 15 and 29.

Referring to the drawings, at 1 is an ordinary table, on which my ironing-machine 55 may rest.

At 2 is a bottom plate, and at 3 3 are fingers permanently secured to said plate, and through which fingers said plate is securely fastened to the table by means of the screw-clamps 4 4. Pivotaly connected to said fixed plate by the pivot-bolt 5 is the plate 6. On this plate are short end pieces 7 7. At 8 is the ironing-board proper permanently fastened at one end to the upper ends of these 65 short pieces 7 7 and extends out horizontally therefrom. The outer end of this board is supported by the supporting-legs 9 9. These legs are preferably formed of wire bent in the inverted-U shape illustrated in Fig. 5 and secured to the under side of said board by means of straps 10 or other convenient means to admit of their being readily turned up out of the way when not in use or when it is desired to draw an article of clothing over the 75 board, such as a shirt or the like.

Hinged at 11 to the attached end of the ironing-board 8 is the upright member 12. On the lower end of this member is the ear 13, through which the screw 14 is threaded 80 and screwed into a corresponding ear 15 in the fixed plate to hold said member 12 in its upright position, as shown in Fig. 1.

At 16 is a horizontal tension-arm connected at one end to the upright member 12 85 by hinges 17 and extends forward over the board, and at 22 is a long coil tension-spring attached to said arm at 23 by a hook and also to the upright at 24 by the hook 25. To the outer end of this arm is attached the sleeve 90 18 through the ball-and-socket joint 19, and secured in this sleeve is the depending rod 21, that has its lower end resting in a recess 26 in the iron 27. The tension on said iron may be made more or less by adjusting this 95 rod vertically in said sleeve and securing the same therein by the set-screw 20. On the rod 21 is the handle 28, by which said rod may be raised and removed from the iron or placed thereon when desired.

100 Sometimes in ironing large articles, such as dresses and the like, it is desirable to swing the board off at right angles to the table and allow it to overhang the same in the manner illustrated in Fig. 2. To do this, it is only 105 necessary to remove the screw 14 from the ear 15 and swing the whole device, with the exception of the bottom plate 2, around at right angles to its original position (shown in Fig. 1) and thread the screw 14 into the ear 110 29 (see Fig. 6) on the back of the fixed plate 2. The end of the board may then rest on

the back of a chair or a long upright 30, if desired.

Another feature of this device that makes it more desirable for household use is the construction which allows of its being collapsed or folded when not in use to admit of its being more readily stowed away.

The device is a labor-saver, is of simple and practical construction, and by its use a high 10 quality of work may be produced.

Having thus described my invention, what I claim as new, and desire to secure by Letters Patent, is—

1. An ironing-machine comprising an ironing-board, an upright member hinged thereto and provided with an overhanging hinged 15 tension-arm, means for locking said member in an upright position, a spring connecting said upright member and said tension-arm, and a tension-rod secured to said tension-arm by a universal joint.

2. An ironing-machine comprising an ironing-board, an upright member hinged thereto and provided with an overhanging hinged 25 tension-arm, means for locking said member in an upright position, a spring connecting said upright member and said tension-arm, and an extensible tension-rod secured to said tension-arm by a universal joint.

3. An ironing-machine comprising a base-plate provided with an ear, an ironing-board supported by said plate, an upright member hinged to said ironing-board and also provided with an ear, means for locking said ears together, whereby said upright member is rigidly supported, and mechanical means carried by said upright member for applying pressure to an iron placed upon said board.

4. An ironing-machine comprising a base-plate provided with a plurality of ears, an ironing-board pivotally supported by said plate, whereby its position may be varied, an upright member hinged to said board and also provided with an ear, means for uniting said latter ear with either of the ears of said plate, whereby said upright member is rigidly supported, and mechanical means carried by said upright member for applying pressure to an iron placed upon said board.

5. An ironing-machine comprising a base-plate, a second plate pivoted thereto and provided with upright end pieces, an ironing-board secured to said end pieces, a support for the free end of said ironing-board, an upright member pivoted to said ironing-board, means for rigidly supporting said upright member, and means carried by said upright member for applying pressure to an iron placed upon said ironing-board.

6. An ironing-machine comprising a base-plate provided with an ear, an ironing-board supported by said plate, an upright member hinged to said ironing-board and also provided with an ear, means for locking said ears together, whereby said upright member is rigidly supported, an overhanging tension-arm hinged to said upright member, a spring connecting said upright member and said tension-arm, and a tension-rod secured to said tension-arm by a universal joint.

In testimony whereof I affix my signature in presence of two witnesses.

HERMAN WONDERLICH.

Witnesses:

E. I. OGDEN,
ADOLPH WONDERLICH.
